[57] CLAIM

The ornamental design for a knee orthosis with strap, as shown and described.

DESCRIPTION

FIG. 1 is a front elevational view of a knee orthosis with strap showing our new design, the broken lines therein being top stitching.

FIG. 2 is a bottom plan view thereof taken along line 2—2 of FIG. 1.

FIG. 3 is a rear elevational view thereof, the broken lines therein being top stitching.

FIG. 4 is a top plan view thereof taken along line 4—4 of FIG. 1.

FIG. 5 is a side elevational view thereof taken along line 5—5 of FIG. 3, the broken lines therein being top stitching.

FIG. 6 is a side elevational view thereof taken along line 6—6 of FIG. 3.
